UNITED STATES PATENT OFFICE.

DAVID OSSRY, OF NEW YORK, N. Y.

IRON-STAND.

1,312,349.

Specification of Letters Patent.

Patented Aug. 5, 1919.

Application filed May 3, 1919. Serial No. 294,561.

To all whom it may concern:

Be it known that I, DAVID OSSRY, a citizen of the United States, and a resident of the city of New York, borough of Manhattan, 5 in the county and State of New York, have invented a new and Improved Iron-Stand, of which the following is a full, clear, and exact description.

This invention relates to an iron stand, 10 and aims more particularly to provide a device of this nature which will render it impossible for the clothes operated on, or the hands of the operator, to become burned by coming in contact with the exterior surface thereof, even although a very hot iron is supported thereon.

A further object of this invention is the provision of an iron stand which shall include heat-insulating structure, which is accomplished by means of permitting a free circulation of air through its parts.

A still further object of this invention is the provision of an iron stand including heat-insulating qualities, which are provided by means of suitable partitions which will confine the heat to certain surfaces only.

And a final object of the invention is to provide an iron stand which shall be extremely simple in construction and, consequently, economical in cost of manufacture.

Reference is had to the accompanying drawings which illustrate one practical embodiment of my improved stand, and in which—

35 Figure 1 is an elevational view of the same applied to an ironing stand;

Fig. 2 is a sectional front elevation through such iron stand;

Fig. 3 is a sectional side view of the same 40 and

Fig. 4 is a top plan view of the support base member of the stand.

In these various views like reference numerals designate similar parts, and the 45 reference numeral 1 indicates a supporting column, which may include drawers 2 for the reception of moistening cloths, pressing cloths, etc. Mounted upon the upper end of this column 1 is a plate 3 having its side edges bent downwardly, as indicated at 4, all such downwardly-bent portions being formed with openings 5 through which are adapted to project securing means, such as screws 6, for retaining the plate 3 in applied position upon the column 1. In addition to the openings 5, one of the downwardly bent

longitudinal side edges is formed with additional openings which receive securing means, such as bolts and nuts 7, which are adapted to maintain in applied position a 60 hinge 8 having secured to it the ironing board 9.

The plate 3 is formed with slits extending through it, for a purpose hereinafter more fully specified; and mounted upon the upper 65 surface of the plate 3 is an inner wall which extends along the two longitudinal edges of the stand and the rear of the same and is provided with tongues 11 adapted to project through the slits 12 and to engage the 70 underside of the plate 3. I wish it understood that the inner wall may be made up of a suitable number of sections, if so desired, or that the same may be stamped from a single piece of metal and bent so as to 75 produce the finished contour desired. The upper edges of this wall are bent outwardly and downwardly and form an outer wall 13 which has its lower edges formed with tongues similar to tongues 11, such as indicated by the reference numeral 14, projecting through slits 15 formed through the plate 3.

Interposed between the inner wall 10 and the outer wall 13, adjacent the hinges 8, 85 there is provided a partition wall 16 which extends from the portion of the metal bridging between the upper ends of the walls 10 and 13 to the upper surface of the plate 3, this partition wall 16 being also provided 90 with tongues 17 which project through slits 18 formed through the plate 13. Nesting between the inner walls 10 is an iron-supporting plate 19 which extends above and in spaced relationship to the plate 3, its inner 95 end being bent downwardly, as indicated by the reference numeral 20, and terminating in tongues 21 projecting through slits 22 in the plate 3. Its front end, however, is bent upwardly, outwardly, and downwardly, as 100 indicated by the reference numeral 23, and also terminates in tongues 24 which project through slits 25 whereby to retain this plate 19 in applied position. A certain portion of the lowermost edge of the part 23 is cut 105 away, as indicated by the reference numeral 26, so that this portion will be spaced from the plate 3 to provide for the circulation of air therebetween. Supporting ribs 27 extend from the outer end of the plate 19 to 110 a point short of the inner, downwardly-bent end of the plate 19. The lower edges

- of these ribs 27 are formed with tongues 28, which also project through slits 29 formed through the plate 3. Preferably formed through the iron-supporting plate 19, the inner walls 10, and the portions projecting between the upper edges of the inner and outer walls, are openings which vary in size, the plate 19 being formed with openings 30, which are larger than openings 31 formed through the inner walls, these openings being, in turn, still larger than the openings 32 formed through the portions extending between the upper edges of the inner walls 10 and the outer walls 13.
- 15 The value of this invention will be perceived in view of the fact that the hand of the operator and the clothes operated upon would normally come in contact with the outer wall 13, which, as it will be appreciated, would never retain any great degree of heat, in view of the space extending between the inner and outer walls, together with the insulating partition therebetween, as well as the openings, providing for a free circulation of air throughout this wall. The same could be said to a lesser extent of the rear walls of the stand and the outer walls thereof, this limitation being included in view of the fact that these walls are not furnished with an interposed partition, such as 16, which is provided in case of the wall extending adjacent the hinges 8, since, as aforesaid, the clothes and hands of the operator would most likely come in contact with this wall.
- It will further be seen that by virtue of the raised end portion of the plate 19, any slipping of the iron from out its stand is effectually prevented. Further, the supporting ribs 27 prevent any sagging on the part of the plate 19 and also perfectly retain this plate spaced from the plate 3, so that a free circulation of air by means of the openings 30 and the cut-away portion 26 is provided for; this function being further insured by reason of the fact that the ribs 27 terminate short of the rear wall of the plate 19, thus allowing a free circulation of air around their rear ends.
- 50 Finally, the various sizes of the openings 30, 31 and 32 make it possible for just the proper amount of air to be circulated through the stand without the strength of the same being sacrificed.
- 55 It is to be appreciated that any number of variations in structure may be resorted to

without in the least departing from the scope of my invention.

Having now described my invention, what I desire to claim is:

1. An iron stand, including a plate, an iron-supporting plate above and in spaced relationship to said first-named plate, inner walls extending around the rear and longitudinal edges of such supporting plate, and outer walls having their upper edges secured to the upper edges of the inner walls, the lower edges of all such walls being secured to the first-named plate. 60
2. An iron stand, including a plate, an iron-supporting plate above and in spaced relationship to said first-named plate, and hollow side walls extending around the rear and longitudinal edges of said supporting plate, one of the longitudinal side walls being formed with a partition extending through its entire length. 70
3. An iron stand, including a plate, an iron-supporting plate above and in spaced relationship to said plate, walls extending from said plate upwardly adjacent the edges of the iron-supporting plate, and ribs interposed between the first-named plate and the iron-supporting plate. 80
4. An iron stand, including a plate, an iron-supporting plate above and in spaced relationship to said plate, walls extending from said plate upwardly adjacent the edges of the iron-supporting plate, and ribs interposed between the first-named plate and the iron-supporting plate, said ribs terminating short of the rear walls. 85
5. An iron stand, including a plate and an iron-supporting plate above and in spaced relationship to said plate, the front edge of said iron-supporting plate being bent upwardly, outwardly, and downwardly and having its lower edge formed with tongues adapted to project through slits formed in the first-named plate. 95
6. An iron stand, including a plate and an iron supporting plate above and in spaced relationship to such plate, such iron-supporting plate having its outer edge bent upwardly, outwardly, and downwardly, a certain portion of the lowermost edge of said supporting plate being cut away, whereby this portion of the iron-supporting plate permits a space to exist between the plate and supporting plate. 100
- 105

DAVID OSSRY.
